UNITED STATES PATENT OFFICE

CHARLES A. CAMPBELL, OF WATERTOWN, NEW YORK, ASSIGNOR TO THE NEW YORK AIR BRAKE COMPANY, A CORPORATION OF NEW JERSEY

SIGNAL

Application filed December 28, 1929. Serial No. 417,142.

This invention relates to signals and particularly to signal discharge valves for pneumatic train pipe signal systems extensively used on railway trains.

In such systems there is a signal train pipe which extends the length of the train. Such train pipe is wholly distinct from the brake pipe and is maintained charged with air under a chosen pressure, say 45 pounds per square inch, by a pressure reducing feed valve deriving air from the main reservoir on the locomotive, and controlled by a choke or restriction which limits the rate of supply to the signal train pipe. There is a diaphragm actuated signal valve on the locomotive, the valve controlling flow of air to the whistle to blow the latter. The diaphragm is subject to train pipe pressure, and so arranged that it opens the valve momentarily and blows the whistle if the train pipe pressure is reduced. Such reductions of train pipe pressure are produced by opening any one of a plurality of discharge valves connected with the train pipe, there being usually at least one such valve on each car. The rate of discharge produced by such discharge valves must exceed the feed rate of the feed valve.

In the signal code from one to seven successive blasts are required, and in long trains, toward which present practice tends, signal failures after two or three blasts are common. The present invention is based on the discovery that these failures are caused by faulty manipulation, and by the uncontrollable characteristics of the simple vent valves heretofore used as discharge valves, which result in excessive venting at each opening of a discharge valve.

The improved discharge valve measures the air discharged at each manipulation, the quantity vented being so chosen as to avoid interference by the feed valve, which starts to feed after the first reduction, and to avoid undue depletion of pressure in the train pipe.

Faulty manipulation is virtually impossible.

In a series of tests on a twenty car train conventionally equipped, the discharge valve on the twentieth car being used, the prior art discharge valve failed after seven blasts with the most favorable manipulation, failed

after one blast in one instance, and averaged 3½ blasts in a series of six graduated tests. The valve here described and claimed, applied to the same signal train pipe, produced twenty-four successive blasts in the poorest test, sixty-three, in the best, and averaged 45½ in a series of six tests which accurately paralleled the series of six made with the prior art valve.

Moreover, the present device does not require the precise manipulation heretofore essential.

The preferred embodiment of the invention is illustrated in the accompanying drawing, in which,—

Fig. 1 is a diagram of the system as a whole for engine tender and three cars.

Fig. 2 is a fragmentary view showing the valve and its connections with the train pipe and measuring chamber.

Fig. 3 is an axial section through the discharge valve.

Fig. 4 is an elevation partly in section on the line 3—3 of Fig. 2.

Referring first to Fig. 1, 5 represents any suitable source of compressed air, conveniently the main reservoir on the locomotive. 6 is a cut-out cock, 7 a strainer, and 8 a pressure reducing feed valve. The feed valve 8 discharges through a flow-limiting choke 9 into the signal train pipe 11. The signal train pipe has the usual hose connections 12 between cars, with cut-out cocks 13. The signal valve 14 on the locomotive is connected with a branch of the signal pipe 11 and controls flow to the signal whistle 15.

All the above parts are of any usual construction. Each car carries at least one of the improved signal discharge valves involving the novel features of the present invention, the preferred embodiment of which will now be described (see particularly Figs. 3 and 4).

On each car there is a branch pipe 16 leading from signal train pipe 11 to a discharge valve generally indicated by the numeral 17 applied to its body. A pipe 18 connects the valve with a measuring chamber 19 (see Fig. 2). The chamber 19 may be of any suit-

able size, but an effective volume of 92 cubic inches has been used with success.

The body 17 is divided into three distinct chambers 21, 22 and 23 by two valve seats 24 and 25 which control ports respectively between chambers 21 and 22 and between chambers 22 and 23. Chamber 21 is vented to atmosphere at 26. Chamber 22 is connected at 27 with branch pipe 18 which leads to the measuring chamber 19, and chamber 23 is connected by union 28 with train pipe branch 16.

Seating upward against seat 25 is the main valve 29 having an extension 30 guided in threaded plug or closure 31. The valve 29 has a sealing insert 32. The valve is urged closed by a spring 33 and its pilot 34 is counterbored to receive the lower end of stem 35 which fits loosely therein. Chamber 21 is open at its upper end and serves as a guide for a combined plunger and spring-seat 36 pinned at 37 to the upper end of stem 35 and protruding from body 17. An actuating lever 38, of the known, double fulcrum type, has hooks 39, 39, engaging the removable fulcrum pins 41, 41, and an eye 42 for the attachment of the usual conductor's signal cord.

The lever 38 engages the member 36 between the hooks 39, and if the lever is swung in either direction from the position shown in Fig. 3, it will depress the member 36 and stem 35 against the resistance of spring 43.

The upper end of stem 35 is reduced in diameter, as shown, to produce a shoulder 44. Slidable on and closely fitting this reduced portion, and limited in its downward motion relatively to stem 35 by shoulder 44 is a valve 45. Valve 45 is urged toward shoulder 44 by spring 46 which reacts between the valve and member 36.

The body 17 is supported fixedly by screws or bolts passing through the lugs 47.

The parts are preferably so proportioned that in normal position (see Fig. 3) valve 45 is held unseated by shoulder 44 and the end of stem 35 is out of contact with valve 29 and spaced far enough from the same to ensure closure of valve 45 against seat 24 before valve 29 is opened by stem 35. Any equivalent arrangement which would ensure closure of valve 45 not later than the initial opening of valve 29 might be used. The simultaneous opening of both valves even for a brief interval would detract from the accuracy of the measuring function and is to be avoided.

To actuate the signal, the lever 38 is swung in either direction from the position of Fig. 3, closing valve 45 and opening valve 29. Pressure equalization occurs between signal pipe 11 and chamber 19. Thus a measured quantity of air is discharged from the signal pipe 11, initiating a pressure wave which travels along the signal pipe to the signal valve diaphragm which responds and blows one

blast of the whistle. When released lever 38 is returned to the position of Fig. 2 by spring 43 causing closing of valve 29 and opening of valve 45 in the order stated, this isolating chamber 19 from the signal pipe 11 and then venting the chamber to atmosphere. The parts are then ready for another manipulation.

As the valves offer short flow paths of large capacity, the air flow is almost instantaneous and precise timed manipulation of the valve is not necessary. If the lever 38 be moved its full stroke a failure to function and blow the whistle under twenty-four successive blasts will not occur, even from the last car of a twenty car train. As such signals are used only on passenger trains, the operation of the device materially exceeds the requirements of service.

The device is illustrated in a form preferred because actual trials demonstrate a high standard of performance, and because susceptible of economical manufacture, but it may be modified in ways which will suggest themselves to those skilled in the art, and still embody the inventive concept.

What is claimed is,—

1. In a signal system, the combination of a source of air under pressure; a signal train pipe; a feed valve delivering air from said source to said pipe and operative at all times to feed air upon a reduction of train pipe pressure and thus tend to maintain a substantially constant pressure in said pipe; means limiting the flow rate through said feed valve; a signal mechanism responsive to pressure reductions in said train pipe; and at least one discharge valve mechanism including a volume measuring chamber adapted when actuated to discharge a measured volume of air from said signal train pipe.

2. In a signal system, the combination of a source of air under pressure; a signal train pipe; a feed valve delivering air from said source to said pipe and operative at all times to feed air upon a reduction of train pipe pressure and thus tend to maintain a substantially constant pressure in said pipe; means limiting the flow rate through said feed valve; a signal mechanism responsive to pressure reductions in said train pipe; and at least one discharge valve mechanism comprising a measuring chamber, two valves, one controlling a vent from said chamber, and the other a passage from the signal pipe to said chamber, and means for opening said valves in alternation with one another.

3. In a signal system, the combination of a source of air under pressure; a signal train pipe; a feed valve delivering air from said source to said pipe and operative at all times to feed air upon a reduction of train pipe pressure and thus tend to maintain a substantially constant pressure in said pipe; means limiting the flow rate through said

feed valve; a signal mechanism responsive to pressure reductions in said train pipe; and at least one discharge valve mechanism comprising a measuring chamber, two poppet valves one controlling a vent from the chamber and the other controlling a connection between the train pipe and chamber, and an actuator having a lost motion connection with both poppet valves, arranged first to

5 seat either valve and then open the other.

10 4. In a signal system, the combination of a source of air under pressure; a signal train pipe; a feed valve delivering air from said source to said pipe and operative at all times to feed air upon a reduction of train pipe pressure and thus tend to maintain a substantially constant pressure in said pipe; means limiting the flow rate through said feed valve; a signal mechanism responsive

15 20 to pressure reductions in said train pipe; and at least one discharge valve mechanism comprising a measuring chamber, two reversely seated poppet valves, one controlling a venting flow from said chamber and opening in the direction of venting flow and the other controlling flow from the train pipe to said chamber and closing in the direction of such flow, spring means urging said poppet valves closed, an actuator mov-

25 30 able in reverse directions to engage and unseat said poppet valves selectively, yielding means urging said actuator in a direction to unseat the first named poppet valve and manual means for shifting said actuator in the reverse direction.

35 5. A signal discharge valve comprising in combination, a measuring chamber; a valve body having a train pipe connection, a connection to said chamber, and a vent; two reversely seated poppet valves in said body, one controlling flow from said chamber to said vent and opening in the direction of venting flow, the other controlling flow from the train pipe connection to said chamber and closing in the direction of flow to the chamber; spring means urging said valves closed; and an actuator movable in reverse directions to unseat said valves selectively.

40 45 6. A signal discharge valve comprising in combination, a measuring chamber; a valve body having a train pipe connection, a connection to said chamber, and a vent; two reversely seated poppet valves in said body, the first controlling flow from said chamber to said vent and opening in the direction of venting flow, the second controlling flow from the train pipe connection to said chamber and closing in the direction of flow to the chamber; an actuator slidable through

50 55 60 65 the first valve and arranged to engage and unseat said valves selectively when shifted in reverse directions; a spring urging said actuator in a direction to unseat the first valve; a spring reacting between the actuator and first valve and arranged to seat said

first valve when the actuator is shifted to unseat the second valve; and yielding means urging the second valve closed.

In testimony whereof I have signed my name to this specification.

CHARLES A. CAMPBELL.
